(57) **CLAIM**

The ornamental design for a hanger for small articles, as shown and described.

DESCRIPTION

FIG. 1 is a perspective view of the hanger for small articles according to the invention;
FIG. 2 is a right side elevation view of the hanger for small articles of FIG. 1, with the left side elevation view being a mirror image;
FIG. 3 is a top plan view of the hanger for small articles of FIG. 1;
FIG. 4 is a bottom plan view of the hanger for small articles of FIG. 1;
FIG. 5 is a front elevation view of the hanger for small articles of FIG. 1;
FIG. 6 is a rear elevation view of the hanger for small articles of FIG. 1;
FIG. 7 is a perspective view of the hanger for small articles according to the invention in a state where engagement of an arm and a hook is released by slightly sliding the arm towards the rear of the hanger;
FIG. 8 is a right side elevation view of the hanger for small articles of FIG. 7, with the left side elevation view being a mirror image;
FIG. 9 is a front elevation view of the hanger for small articles of FIG. 7;
FIG. 10 is a perspective view of the hanger for small articles according to the invention in a state where the arm has rotated by approximately 80 degrees upwards with regard to the hook;
FIG. 11 is a right side elevation view of the hanger for small articles of FIG. 10;
FIG. 12 is a top plan view of the hanger for small articles of FIG. 10;
FIG. 13 is a front elevation view of the hanger for small articles of FIG. 10;
FIG. 14 is a perspective view of the hanger for small articles according to the invention in a state where the hook has rotated by approximately 90 degrees with regard to a base; and,
FIG. 15 is a front elevation view of the hanger for small articles of FIG. 14.
